US00D744886S

(12) **United States Design Patent**
Oh

(10) **Patent No.:** **US D744,886 S**
(45) **Date of Patent:** **** Dec. 8, 2015**

(54) **WHISTLE CLASP**

(71) Applicant: **Knottology, LLC**, Kalamazoo, MI (US)

(72) Inventor: **Hyeon Jin Oh**, Kalamazoo, MI (US)

(73) Assignee: **KNOTTOLOGY, LLC**, Kalamazoo, MI (US)

(**) Term: **14 Years**

(21) Appl. No.: **29/473,259**

(22) Filed: **Nov. 20, 2013**

Related U.S. Application Data

(63) Continuation-in-part of application No. PCT/US2013/040366, filed on May 9, 2013.
